UNITED STATES PATENT OFFICE

146,808

DESIGN FOR A BOX OR SIMILAR ARTICLE

Gaetano Restifo, Jackson Heights, N. Y.

Application April 12, 1946, Serial No. 128,518

Term of patent 3½ years

(Cl. D58—12)

To all whom it may concern:

Be it known that I, Gaetano Restifo, a citizen of the United States of America, residing in Jackson Heights, county of Queens, and State of New York, have invented a new, original, and ornamental Design for a Box or Similar Article, of which the following is a specification, reference being had to the accompanying drawing, forming part thereof.

In the drawing:

Figure 1 is a perspective view of a box or similar article embodying my new design;

The side panel opposite to the side panel shown in Figure 1 is identical with the one shown in the drawing, and the end panel opposite to the end panel shown in Figure 3 is identical with the one shown in the drawing.

The bottom of the box is plain.

The design shown in the drawing has a raised or embossed appearance.

I claim:

The ornamental design for a box or similar article, substantially as shown and described.

GAETANO RESTIFO.
